SANTA CLAUS RED NOSE NOVELTY PULL CORD
FLASHLIGHT

Albert Gelardin, New York, N. Y.

Application December 14, 1953, Serial No. 28,035

Term of patent 14 years

(Cl. D48—24)

FIG. 1.

FIG. 2.

FIG. 4.

FIG. 3.

To all whom it may concern:

Be it known that I, Albert Gelardin, a citizen of the United States and a resident of the city, county, and State of New York, have invented a new, original, and ornamental Design for a Santa Claus Red Nose Novelty Pull Cord Flashlight, of which the following is a specification, reference being had to the accompanying drawings, forming part hereof and in which:

Fig. 1 is a front elevational view of a Santa Claus red nose novelty pull cord flashlight showing my new design.

Fig. 2 is a rear elevational view.

Fig. 3 is a side elevational view.

Fig. 4 is a top elevational view.

I claim:

The ornamental design for a Santa Claus red nose novelty pull cord flashlight, as shown.
